DESIGN FOR A WEIGHING SCALE

William O'Neil, New York, N. Y., assignor to
Pitney-Bowes, Inc., Stamford, Conn., a corpora-
tion of Delaware

Application October 16, 1948, Serial No. 149,144

Term of patent 14 years

(Cl. D52—10)

To all whom it may concern:

Be it known that I, William O'Neil, a citizen of the United States, residing at New York, in the county of New York and State of New York, have invented a new, original, and ornamental Design for a Weighing Scale, of which the following is a specification, reference being had to the accompanying drawing, forming part thereof, wherein:

Fig. 1 is a perspective view of a weighing scale looking downward and toward the weighing platform end thereof showing my new design; and

Fig. 2 is a perspective view taken from the opposite end of Fig. 1 and particularly showing the side thereof.

The side of the scale not shown is the same in appearance as that shown in Figs. 1 and 2.

I claim:

The ornamental design for a weighing scale, as shown and described.

WILLIAM O'NEIL.
